UNITED STATES PATENT OFFICE

2,467,551

PRODUCTION OF AROMATICS

Everett Gorin, Dallas, Tex., and John R. Vorwerck, Maplewood, La., assignors, by mesne assignments, to Socony-Vacuum Oil Company, Incorporated, New York, N. Y., a corporation of New York

No Drawing. Application March 2, 1945,
Serial No. 580,716

13 Claims. (Cl. 260—673)

1

This invention relates to the pyrolysis of methane or natural gas for the production of aromatic hydrocarbons. This application is a continuation in part of our copending application, Serial No. 399,942, filed June 26, 1941, now abandoned, and is concerned particularly with the production of benzene from methane.

The formation of benzene by the pyrolysis of normally gaseous hydrocarbons such as methane, ethane and propane, is known. However, for example, in the strictly thermal conversion of methane to benzene, the benzene only becomes quantitatively measurable at temperatures above about 900° C. By increasing the temperature the yield will show a gradual rise up to 6-10% at 1200°-1300° C., and then it begins to fall off as the reaction temperature is raised still higher. Numerous attempts have been made to discover catalysts or other means for aiding the pyrolysis of methane to benzene in order that lower reaction temperatures may be used and the yield of benzene increased. These attempts have been rather uniformly unsuccessful.

It, therefore, is an object of our invention to provide an improved process of converting normally gaseous hydrocarbons such as methane or a dry natural gas to light aromatic hydrocarbons. Another object is to afford a process of converting methane to aromatic hydrocarbons which is an improvement over strictly thermal processes for accomplishing such a conversion. Another object is to afford an improved process of converting a dry natural gas, substantially free of condensable hydrocarbons to light aromatics at temperatures below 1000° C. A more specific object is to provide a process of converting methane to benzene in substantial amounts at temperatures below 1000° C. These and other objects will be apparent from the description of our invention.

We have found that by carrying out the pyrolysis of methane in the presence of relatively large amounts of free chlorine or free bromine and for a sufficient length of time to convert at least a predominant portion of the chlorine or bromine to the corresponding hydrogen halide state we may employ temperatures below 1000° C. and the overall operation is thermoneutral or even exothermic. Further, by carrying out the pyrolysis in the presence of a large amount of chlorine or bromine we obtain at any given temperature a substantially increased yield over that obtained at the same temperature in a strictly thermal process, or we can use a substantially lower temperature to obtain the same yield.

2

We have also found that if we operate our process at temperatures substantially above 1000° C. the reaction tends to produce unsaturated aliphatic hydrocarbons such as acetylene and ethylene. Hence we prefer to operate our process at temperatures below 1000° C. to produce benzene and homologs of benzene.

The chlorine or bromine used in our process may be designated a reaction promoter rather than a catalyst since the halogen is chemically bound during the reaction to form a hydrogen halide. As a result we obtain the very desirable thermal advantage made possible by the high exothermal reaction of the halogen to form the hydrogen halide. Thus, in the prior art the pyrolysis reactions are highly endothermic, requiring a large heat input at a very high temperature level, i. e., above 1000° C. Such a requirement, obviously, imposes a considerable complexity of apparatus and technique on these prior methods. On the contrary, if the principles of our invention are followed so that a large amount of chlorine or bromine is used as a reagent, and contact times are employed which result in substantially all the chlorine and bromine being converted to the hydrogen halide, then the overall reaction is exothermic. The operating and economical advantages afforded by this latter type process are readily apparent.

30 Therefore, one of the outstanding features of our invention is the provision of a process of converting methane to benzene that is not endothermic. This fact is strikingly illustrated by the following comparison of the heat requirement of our process with a strictly thermal process.

40 Another very important aspect of this invention is that it permits the production of benzene from methane at temperatures below 1000° C. The process may be operated at temperatures up to 1200° C. as in the thermal process. However, as stated hereinabove, the tendency to obtain less yield of aromatics and higher yields of acetylene increases if temperatures above 1000° C. are used, especially if relatively short contact times are employed. We prefer to employ contact times of from about three seconds to sixty seconds.

45 The contact time as used herein is expressed as the volume of reaction space divided by the average rate of flow of gas at standard conditions

of temperature and pressure through the reactor, that is, the reciprocal of space velocity. The actual residence time is considerably shorter than this and may be determined from the contact time by multiplying by the factor

273

7

where T is the temperature in degrees Kelvin in the reaction zone.

The amount of chlorine or bromine reagent required for our process may vary considerably depending on the extent to which we desire to utilize the exothermic heat of conversion of the halogen to the hydrogen halide. We use a minimum amount of halogen of 15% by volume of the mixture of halogen and methane or 15% by volume of the mixture of halogen and dry natural gas feed to the process, and we prefer to use from about 15% to 30% by volume of chlorine or bromine and not more than 40% by volume of halogen in the hydrocarbon-halogen reaction mixture in our operations.

The temperature of operation should be above about 700° C. Thus, in our preferred operation we employ temperatures between about 700° C. and 1000° C. It is not necessary to maintain uniform temperature throughout the conversion zone for the successful operation of our process. Thus, the chlorine and methane mixture may be reacted initially for short contact times at temperatures in the neighborhood of 1000° C., and the product gases then allowed to cool gradually to temperatures of the order of 700° C. before issuing from the conversion zone. If desired, temperatures up to 1200° C. may be used to obtain yields of aromatics greater than obtainable by strictly thermal processes in the absence of promoters, although in the upper temperature range the tendency to form unsaturated aliphatics is increased. The preferred range of contact times above refer to the total time of contact of the gas mixture in the whole conversion zone.

The operating procedure for our process may be substantially the same as that known to those skilled in the art for thermally converting methane to benzene. Thus, the methane, after removal of sulfur, if necessary or desired, may have the proper amount of halogen reagent added to it and the mixture is then passed at conversion temperatures through a conventional converter. Liquid bromine may be supplied to the gaseous hydrocarbon reactant by bubbling the latter through the bromine to incorporate therein the gaseous bromine volume content within the above limits or chlorine may be added directly as a gas to the hydrocarbon gas. It is to be understood, however, that the halogen reagent may be introduced in any other suitable manner. For example, because of the highly exothermic nature of the reaction caused by the halogen it may be desirable to introduce this reagent at a plurality of points along the converter in order to obtain better heat distribution and hence improved temperature control. Further, it is to be understood that the total yield of benzene may be increased by further pyrolysis of product gases from which benzene has been removed.

In order that the invention may be illustrated more fully, the following specific examples are given. It is to be understood that the process is not limited to the specific details of these examples, as there may be variations therefrom

without departing from the scope of the invention.

Example I

A methane-bromine mixture, containing 17% by volume of bromine was pyrolyzed at 925° C. for 24 seconds and gave a yield based on the methane input of 8.6 mol per cent of benzene and 6.7 mol per cent of acetylene. Thus, it will be noted that the yield of benzene obtained in this experiment is superior to that obtained from pure methane alone under any conditions at a temperature below 1000° C. Thus, for example, a comparative experiment made with pure methane alone under the same condition yielded an almost negligible conversion to benzene.

Example II

A methane-bromine mixture, containing 21% by volume of bromine was pyrolyzed at 775° C. with a contact time of 52 seconds. Based on the methane input, a yield of 4.7 mol per cent benzene, 1.8 mol per cent acetylene and 3.4 mol per cent of ethylene was obtained. The bromine was completely consumed to produce hydrogen bromide.

Example III

A methane-bromine mixture, containing 20% by volume of bromine was pyrolyzed at 1000° C. with a contact time of 11.8 seconds. This operation gave a yield in mol per cent, based on the methane input, of 11.0 per cent benzene and 7.8 per cent acetylene.

Example IV

A methane-chlorine mixture containing 31% by volume of chlorine was pyrolyzed at 825° C. with a contact time of 23 seconds. Based on the methane input, a yield of 11.3 mol per cent benzene and 4.2 mol per cent of acetylene was obtained. Thus, it is seen that an increase in the amount of halogen increases the relative amount of benzene with respect to acetylene produced. In a comparative operation under the same conditions except that no reaction promoter was used, the yield of benzene and other useful products was negligible.

Example V

Methane and chlorine were mixed in the ratio of 65 parts by volume of methane to 35 parts by volume of chlorine, and the mixture was passed at a contact time of 0.045 second through a quartz reaction tube maintained at 1020° C. After removal of the hydrogen chloride the effluent gas had the following composition: C₂—C₆ unsaturated gases, that is, acetylene, ethylene, butadiene, vinyl acetylene, etc., 10.0 vol. per cent, 0.8 vol. per cent of C₆+polymers, 3.2 vol. per cent hydrogen, 14.7 vol. per cent methyl chloride, 3.5 vol. per cent methylene chloride and the remainder unconverted methane. The C₆+polymers consisted of highly unsaturated materials such as divinyl acetylene and contained little or no benzene. The total conversion of methane to higher hydrocarbons amounted to 27.0% of the methane passed. This operation illustrates the inadequacy of short contact times in the production of benzene with chlorine as a reagent.

Example VI

A mixture containing 33 mol per cent of chlorine and 67 mol per cent of methane was pyrolyzed at 960° C. and a contact time of 0.3 second. The effluent gas after removal of hydrogen chloride contained 6.4% acetylene but no benzene, thus

illustrating again the necessity for adequate contact time in our process for producing benzene from methane.

Some methyl chloride is always formed as an intermediate and a small amount may remain in the effluent gas particularly when temperatures below 800° C. are employed. It is generally desirable to recycle the total effluent gas to the pyrolysis zone after removal of the hydrogen chloride and aromatic products. Under these conditions any methyl chloride present is further pyrolyzed to produce hydrogen chloride and aromatic hydrocarbons. By such a recycling procedure an ultimate yield of 60% of aromatic hydrocarbons boiling in the gasoline range may be obtained while the remainder of the methane is converted to aromatic tars and carbon. The regeneration of the free halogen acid by-product may be accomplished in any suitable manner known to the art for such purposes.

The invention has been described with particular reference to the conversion of methane to benzene for the sake of simplicity. However, it is to be understood the invention is applicable to the treatment of mixtures of methane and ethane such as found in a dry natural gas containing no more than a trace of condensable hydrocarbons. Such a high methane-ethane content gas may occur naturally or it may consist of a residue gas obtained by removing the condensables and a substantial part of the propane from a wet natural gas. Such a dry natural gas will usually contain a minimum of 95 vol. per cent of methane plus C₂ hydrocarbons. The methane plus C₂ hydrocarbon content of residue dry gas obtained from very "wet" natural gas by removal of condensables, including with condensables a substantial part of the propane content of the wet gas, may be as low as 90 vol. per cent. Our invention should be construed to include such a residue gas as being within the definition of a dry natural gas.

We claim:

1. The process of converting a dry natural gas to liquid aromatic hydrocarbons which comprises pyrolyzing a mixture consisting essentially of from 85 to 60 parts by volume of said natural gas with from 15 to 40 parts by volume of a halogen selected from the class consisting of chlorine and bromine at a temperature within the range of from about 700° C. to about 1000° C. and regulating the contact time so that substantially all of said halogen is converted to the hydrogen halide.

2. The process of converting methane to benzene which comprises pyrolyzing a mixture consisting essentially of from 85 to 60 parts by volume of methane with from 15 to 40 parts by volume of a halogen selected from the group consisting of chlorine and bromine at a temperature within the range of 700° C. to 1000° C. at sufficient contact time of the reactants such that substantially all of said halogen is converted to the hydrogen halide.

3. The process as described in claim 2 wherein the halogen is chlorine.

4. The process of claim 2 wherein the halogen is bromine.

5. The process of claim 2 wherein the halogen and methane are contacted at a temperature within the range of 800° C. to 1000° C. for a period of time within the range of from about 3 seconds to about 60 seconds.

6. The process of manufacturing normally liquid aromatic compounds from a hydrocarbon gas containing a minimum of 90 per cent of methane plus C₂ hydrocarbons which process 5 comprises pyrolyzing a mixture of from 85 parts by volume to 60 parts by volume of said methane and C₂ hydrocarbon containing gas with from 15 parts by volume to 40 parts by volume of a halogen selected from the class consisting of chlorine and bromine at a temperature within the range of from 700° C. to 1000° C. and regulating the contact time of said hydrocarbon gas with said halogen within the range from 3 seconds to 60 seconds so that substantially all of the said halogen is converted to hydrogen halide.

7. The process of claim 6 wherein the hydrocarbon gas is a natural gas from which the major part of C₃ hydrocarbons and substantially all of the hydrocarbons having more than three carbon atoms per molecule have been removed.

8. The process of claim 6 wherein the halogen is chlorine.

9. The process of claim 6 wherein the halogen is bromine.

10. The process of manufacturing benzene from methane which comprises pyrolyzing a mixture consisting essentially of from 85 to 70 parts by volume of methane with from 15 to 30 parts by volume of a halogen from the group consisting of chlorine and bromine at a temperature above 700° C. but not exceeding 1000° C. and regulating the contact time of the reactants within the range of from 3 to 60 seconds so that substantially all of said halogen is converted to the hydrogen halide.

11. The process of claim 10 wherein the halogen is chlorine.

12. The process for manufacturing benzene from a dry natural gas of which at least 95 volume percent of the hydrocarbons therein contain not more than two carbon atoms per molecule which comprises pyrolyzing a mixture consisting of from 85 to 70 parts by volume of said natural gas based on the hydrocarbons therein with from 15 to 30 parts by volume of a halogen selected from the group consisting of chlorine and bromine at a temperature above 800° C. but not exceeding 1000° C. and regulating the contact time of the reactants within the range of from 3 to 60 seconds so that substantially all of said halogen is converted to the hydrogen halide.

13. The process of claim 12 wherein the halogen is chlorine.
